O. W. L. BUSS

HINGE

Filed Dec. 22, 1923

Inventor
OTTO W.L. BUSS

By Paul, Paul Moore

ATTORNEYS

UNITED STATES PATENT OFFICE.

OTTO W. L. BUSS, OF MINNEAPOLIS, MINNESOTA.

HINGE.

Application filed December 22, 1923. Serial No. 682,190.

This invention relates to improvements in hinges and more particularly relates to hinges of the general type wherein the two relatively movable members are readily separable. Such hinges, while useful for the pivotal support of doors, windows and similar objects of various types, are particularly useful for the readily separable mounting of such objects in a suspended or hanging operative position such as is common in basement windows, storm sashes, etc.

The object therefore of this invention is to provide an improved hinge.

Other objects of the invention will more fully appear from the following description and the accompanying drawings and will be pointed out in the annexed claims.

In the accompanying drawings, there has been disclosed a structure designed to carry out the objects of the invention but it is to be understood that the invention is not confined to the exact features shown, as various changes may be made within the scope of the claims which follow.

In the drawings:

Figure 1 is a perspective view of the operatively assembled hinge with portions of a window frame and sash;

Figure 2 is a view similar to that of Figure 1, but in front elevation;

Figure 3 is a vertical sectional view on the line 3—3 of Figure 2; and

Figure 4 is a view similar to that of Figure 3 but with the parts in position for assembly or separation.

The embodiment of this novel hinge which has been selected for the purpose of explanation of the invention is one more particularly adapted for use in separably mounting a basement window sash of the general type shown in applicant's prior pending application Serial Number 677,040, filed November 26, 1923, for window structures, wherein this novel hinge is also shown.

The window frame 5 is shown as having a plate-like member secured thereto by rivets 6. This member is preferably metallic and consists of a plate 7 having its lower portion marginally turned or curved upwardly toward itself to form an interiorly rounded bearing portion 8. The upper or inner edge of this bearing portion does not abut against the adjacent face of the plate 7 but is spaced therefrom. Preferably, this margin is formed with an integral abutment 9 which may conveniently be left when this bearing

member is stamped out. The bearing portion may thus be turned until the abutment is against the face of the plate 7 in which position it may be welded and thus aid in the rigid support of this bearing portion. This abutment 9 is formed on the lower edge of the plate 7 at a position intermediate its ends, as here shown it is at the median portion. Thus, the major portion of this edge of the bearing portion is spaced from the plate or each side of this median abutment. This space or these two spaces are provided for the reception or separation of the pintle-forming parts of the hinge.

The pintle element of this novel hinge is here shown as a metallic plate 11 held to a sash 12 by rivets 13. Means project from this element on each side thereof and are adapted to be operably received in, and separable from, the bearing portion 8 of the relatively fixed plate 7 of the hinge. These projecting means are here shown as the two rods 14 and 15, one being welded or similarly secured to each vertical side of the plate 11. The upper end of each rod is terminally offset each toward the other so that these offsets may conjointly form the pintles 16 and 17 in axial alinement. These pintles are similar in shape and each is of elongated cross-section, such as an oblong with its shorter edges rounded. The smaller axis of each pintle is less than the space between the inwardly turned edge of the bearing portion 8 and the face of the relatively fixed hinge plate 7 while the larger axis is greater. Therefore, when the sash 12 is swung to the position indicated in Figure 4, the pintles may be passed through such space or spaces and the pintles may be operably seated or may be removed therefrom. This conformation of the pintles also prevents the separation of the hinge parts and hence removal of the sash when the sash is in normal open or closed positions as is suggested in the vertical sectional view in Figure 3. The ready separation of the hinge parts is effected by a lifting movement of the sash in the direction of the shorter axes of the pintles when in the position shown in Figure 4 wherein the sash is substantially at a right angle to the frame. Obviously, however, the axes of the pintles may be changed so that the sash may be demounted when held in positions other than substantially at right angles, as shown. While the adjustment shown is usually preferred there

are sometimes installations of frames where-in the designated demounting movement is obstructed. In such cases the pintle axes may be changed.

5 The shorter sides of the pintles 16 and 17 are preferably rounded as is shown in order to reduce friction in their engagement with the rounded interior surface of the bearing portion 8.

10 The construction of this novel hinge is one that readily lends itself to inexpensive and economical quantity production. It is smooth and certain in operation, is not liable to derangement and the parts may 15 be quickly and easily separated and assembled without tools by those unskilled in this art.

Having thus described my invention what I claim as new and desire to secure by Letters-Patent, is:

20 1. A hinge comprising a member having a planiform body portion marginally turned toward itself along one end to provide a bearing, the inner edge of the bearing portion being uniformly spaced from the body of said member to form a longitudinal slot parallel with the body portion of said member, an abutment integrally formed on the

edge of said marginal portion of a length equal to the width of said slot and abutting 30 against said body portion, and a complementary hinge member comprising a planiform body portion having oppositely facing pintle members secured to said body portion being of substantially rectangular cross section and of a width equal to the width of said slot, said pintle members terminating short of one another a distance equal to the width of said abutment and adapted to straddle said abutment upon insertion thereof into said slots.

2. In a hinge the combination of a plate-like member marginally curved toward itself to provide a bearing portion, the inner edge of the bearing portion being substantially spaced from the member, means located at an intermediate position on said edge to secure the curved bearing portion to the member across said space, a pintle element separable from said member, means projecting from the element and adapted to be operably received in, and separable from, said bearing portion through said space.

In witness whereof, I have hereunto set my hand this 20th day of December, 1923.

OTTO W. L. BUSS.
